UNITED STATES PATENT OFFICE

2,265,644

LAMP

Frederick R. Hodges, Chicago, Ill.

Application February 17, 1939, Serial No. 256,902

5 Claims. (Cl. 240—81)

This invention relates to a light fixture, and has for one object to provide in connection with a light fixture which has one or more main light sources an auxiliary or "night light." Another object is to provide in connection with such a light fixture an auxiliary light which occupies space which would otherwise be unoccupied. A further object is to provide in connection with a lighting fixture of the type indicated in which a housing is provided for electric wires or switches or the like an auxiliary light within one of such housings. A still further object is to provide in connection with a fixture of the type indicated an enclosed or housed auxiliary light, which light is housed or enclosed within structural members that would be present whether the auxiliary light were supplied or not.

Other objects will appear from time to time throughout the specification and the claims.

The invention is illustrated more or less diagrammatically in the accompanying drawing, wherein:

Figure 1 is a side elevation of one form of the light with parts broken away;

Figure 2 is a vertical section taken on an enlarged scale at line 2—2 of Figure 1;

Figure 3 is a side elevation of a modified form of housing or shell with parts broken away and parts in section.

Like parts are designated by like characters throughout the specification and the drawing.

While the features of my invention may be applied to lights of many sorts, such as standing lamps or table lamps, the invention is not limited to any particular type of lamp or base. It is shown here, however, as applied to a standing lamp, which comprises a base 1, an upwardly extending ornamental shaft or housing 2, within which may be positioned a load-carrying member 3, which is preferably tubular in shape and encloses the lighting connections.

A housing 4 of rounded or partially globular shape is secured to the tube 3, and held down upon it and in engagement with the upper end of the tube 2 by a nut 5, which is threaded on the upper end of the member 3. A plurality of candle brackets 6 may be joined to the housing 4 and, as shown, support candle-like fixtures 7, which carry lights or globes 8. Positioned upon the housing member 4 is a second housing member 9, which is provided with a flange or bead 10 about its lower edge. At one side, the bead 10 engages a projection 11, formed in the housing 4. At the other side, it is secured by a screw 12 to the housing 4.

Positioned largely within the housing section 4 is a reflector and partition 13. It may have a laterally extending edge portion 14, which in the form here shown is engaged between the upper edge of the housing 4 and the lower or downward shoulder 15 of the upper housing 9. Obviously, the reflector might be positioned otherwise. The housing member 9 is provided with a plurality of perforations 16, which may be of any size or shape. They might be, as here shown, a number of relatively small perforations, or might be slots or might be otherwise made.

At its upper end, the housing 9 is provided with an internally threaded section 17, which may, as here shown, be integral with the housing, or might be otherwise made. One or more ornamental discs 18, 18 may be positioned on the upper end of the housing 9. As shown, these discs have ornamental flanges 19, which are positioned outwardly and serve as ornamental features. A shell 20, which is nicked in as at 21, rests upon the uppermost flange 18. It is perforated to permit a tubular member 22 to pass through. This member is threaded as at 23, and engages the threaded portion 17 of the housing 9, and holds the parts in place. For some purposes, it is desirable to provide a tubular casing 24 about the member 22. In general, the member 22 serves to carry wires 25 upward to a lighting socket, 30 which is not shown. The shell 20 may be enlarged adjacent its upper end, as at 26, to receive a light bowl 27. A shade 28 is suspended from or supported upon the bowl by members 29. An electric light bulb 30 is positioned in the fixture contained in the shell portion 20, 26.

Positioned within the housing formed by the members 4 and 9, and preferably suitably attached to the reflector 13, is a socket member 31, which is provided with an insulating collar 32, holding it out of contact with the reflector 13. An electric light bulb 33 is removably positioned within the socket 31. Wires 34, 34 are connected to the socket 31, and are then connected to the housing 35 of a switch. A switch-operating button or handle 36 extends outwardly from the housing, and serves for turning the light off and on.

In the modified form of Figure 3, the internal construction is substantially that shown in Figure 2; but the upper part of the housing member or shell construction is different and comprises a tubular member 37, having an outwardly flared bottom bead 38, substantially like that shown in Figure 2. A partition 39 may be formed within it to support the tubular member 24, which

is the same as that shown in Figure 2. A nut 40 holds the tubular member in place. The shell 37 is upwardly enlarged as at 41 to receive the light and the light bulb or bowl. 42 is a switch button by means of which the main light is controlled.

While it is not shown, there will ordinarily be provided a separate control or button for the candle brackets, and the completed light, thus, comprises a second control for the candle brackets, and a third control for the auxiliary or "night light." In the modified form of Figure 3, the shell portion 37 is provided with slots 43; but in this form of shell any other form of opening might, if desired, be provided.

Although I have shown an operative form of my device, it will be understood that many changes in the form, shape and arrangement of parts might be made without departing from the spirit of my invention; and I wish that my showing be taken as in a sense diagrammatic.

I claim:

1. In combination in an electric lighting fixture, a base member, a supporting standard secured to and extending upwardly from said base, a two-part housing carried by the standard at its upper end, the said housing including a lower housing member secured to the upper end of the standard, and an upper housing member removably supported upon the lower housing member, a main outer lighting fixture carried by said upper housing member, an auxiliary lighting fixture, means to support the auxiliary lighting fixture within said housing, the enclosing wall of said housing member being perforated whereby light from said auxiliary fixture is visible through said perforations, said auxiliary lighting fixture supporting means including a reflector member supported from the upper end of said lower housing member and carrying said auxiliary lighting fixture centrally thereof.

2. In combination in an electric lighting fixture, a base member, a supporting standard secured to and extending upwardly from said base, a two-part housing carried by the standard at its upper end, the said housing including a lower housing member secured to the upper end of the standard, and an upper housing member removably supported upon the lower housing member, a main outer lighting fixture carried by said upper housing member, an auxiliary lighting fixture, means to support the auxiliary lighting fixture within said housing, the enclosing wall of said housing member being perforated whereby light from said auxiliary fixture is visible through said perforations, said auxiliary lighting fixture supporting means comprising a fixture supporting partition member having a peripheral flange seated upon the upper edge of said lower housing member, said upper housing member seating upon said flange to secure the partition member between the upper and lower housing members,

said upper housing member having at its lower end a depending peripheral flange telescopically engaging the upper end of the lower housing member, and means for detachably securing the upper housing member in position.

3. In combination in an electric lighting fixture, a base member, a supporting standard secured to and extending from said base, a hollow housing secured to said standard, a main outer lighting fixture carried by said housing member, a side lighting fixture projecting from said housing member, and lights positioned in said main outer lighting fixture and in said side lighting fixture, electric conductors leading through said housing member to said main outer lighting fixture and to said side lighting fixture, and an auxiliary lighting fixture positioned within said housing, electric conductors therefor within said housing member, means to support said auxiliary lighting fixture within said housing, an enclosing wall of said housing member being adapted to transmit light from said last mentioned auxiliary lighting fixture.

4. In combination in an electric lighting fixture, a base member, a supporting standard secured thereto and extending upwardly therefrom, and means for supporting from said standard a plurality of lighting fixtures and for supporting and enclosing electric conductors therefor, said means including a hollow housing positioned substantially upon the upper end of said standard, and a main outer lighting fixture positioned upon an upper portion of said housing, and a laterally directed side lighting fixture supported from a side portion of said housing, and electric conductors for said lighting fixtures, said conductors being positioned in part within said housing and extending into said lighting fixtures, and lights on said fixtures, and an additional auxiliary light, said light being positioned within said housing, and means within said housing for supporting said light, said housing provided with openings through which said auxiliary light may cast illumination.

5. In combination in an electric lighting fixture, a base member, a supporting standard secured to and extending upwardly from said base, a housing carried by the standard at its upper end, the said housing comprising superposed separable parts and including a lower housing member secured at the upper end of the standard, and an upper housing member removably supported upon the lower housing member, a main outer lighting fixture carried by said housing, an auxiliary lighting fixture supporting means carried by said housing between said superposed parts for supporting the auxiliary lighting fixture within the housing, the enclosing wall of said housing being perforated whereby light from said auxiliary lighting fixture is visible through said perforations.

FREDERICK R. HODGES.
